Patented Feb. 8, 1966

203,724

COMBINED DESK SET, CALENDAR AND TELEPHONE INDEX

Johan Samuel Zandelin, Gammelgardsvogen 20,
Stockholm, Sweden

Filed Sept. 14, 1964, Ser. No. 81,713

Term of patent 14 years

(Cl. D74—1)

FIG. 1 is a front perspective view of a combined desk set, calendar and telephone index showing my new design, the back thereof being plain and unornamented; and

FIG. 2 is a side view of the same.

I claim:

The ornamental design for a combined desk set, calendar and telephone index, substantially as shown and described.
